UNITED STATES PATENT OFFICE

AINSLEY J. VINCENT, OF LAWRENCE, MASSACHUSETTS

WINDOW AND SCREEN THEREFOR

Application filed July 30, 1928. Serial No. 296,272.

This invention relates to a window frame having a screen guiding rib on the inner edge of, and integral with, an upright outside member thereof, and a screen frame slidable on the rib.

The object of the invention is to provide an improved form of the rib whereby a thick and massive form is imparted thereto, reducing liability of breakage of the integral rib from the casing member.

Of the accompanying drawings forming a part of this specification,—

Figure 1 is a fragmentary perspective view, showing a portion of a window frame, the outside casing member of which is provided with my improved guiding rib.

Figure 2 is a fragmentary horizontal section, showing a portion of the outside casing member having the improved guiding rib, a portion of the pulley stile, a portion of an upper sash, and a portion of a screen frame provided with a spring, the screen frame and spring being engaged with the rib.

Figure 3 is a section on line 3—3 of Figure 2.

Figure 4 is a view similar to a portion of Figure 2, showing the spring displaced to permit the removal of the screen from the window frame.

Figure 5 is a perspective view of the spring.

Figure 6 is a section on line 6—6 of Figure 5.

Figure 7 is a fragmentary sectional view, showing portions of two outside upright casing members, and portions of two upright screen-frame members.

Figure 8 is a view similar to Figure 7, showing a modification.

Figure 9 shows separately a portion of one of the outside casing members.

The same reference characters indicate the same parts in all of the figures.

Figure 1 shows a portion of one of the upright sides of a window casing, the opposite side being similarly constructed.

12 designates the inside vertical casing member, 13 the outside vertical casing member, and 14 the pulley stile, the upper portion of which supports the pulleys on which are

trained the sash cords supporting the usual sash weights movable in the vertical well formed by the members 12 and 13 and the stile 14. The stile is joined to and connects the members 12 and 13, as usual. 15 designates a portion of the stool or sill member of the casing, joined as usual to the lower ends of the casing members and stile. The inner edge portion of the outside member 13 has a sash guiding face 35, and projects across the sash-guiding inner face of the stile to cooperate with the stile and the usual parting bead 16 in guiding the upper sash 17. The lower sash (not shown) is guided by the stile, the parting bead and the inside stop bead, as usual.

The inner edge of the outside member 13 is provided with a longitudinal rib, which is an integral part of the member, and has a lip-guiding inner face 20, a screen-guiding outer face 21, and an intermediate spring-guiding face 22, on which a spring attached to a screen frame is slidable. The face 21 is in a plane parallel with the outer side of the casing member 13, and is considerably wider than the face 20, and provides a wide insect-excluding bearing for a portion of the screen frame. 24 designates one of the upright members of a screen frame in which is formed a longitudinal groove wider than the rib and having a wide outer wall provided with a wide side face 25, slidable on the wide rib face 21, and suitably overlapping the latter to exclude insects. The groove has a narrow inner wall provided with a side face 26. The two side faces intersect the bottom face 27, to form a groove which is deeper at one edge than at the other, the width of the side face 26 being such that the screen frame is adapted to be moved outwardly from the position shown by Figures 2 and 4, across the rib face 22.

28 designates a curved metal spring, the end portions of which bear on the bottom of the screen groove and are secured thereto by fasteners 29, the spring being provided with orifices 30, receiving said fasteners and preferably elongated, as shown by Figure 5, to permit the straightening displacement of the spring, as hereinafter described. The curva-

ture of the spring is such that its midlength portion normally projects outside the narrow face 26 of the groove, and is in slidable contact with the spring guiding rib face 22. On the inner edge of the midlength portion of the spring is an outwardly projecting confining lip 31, held by the spring in slidable engagement with the inner rib face 20, as shown by Figure 2, to prevent removal of the screen frame from the window frame.

The narrow inner face 20 of the rib is parallel with the outer face 21, is offset from the sash guiding face 35 and is arranged to guide the spring lip 31.

15 The rib includes a reinforcing fillet portion 33 integral with the rib and the casing member 13 and having a beveled face 33^a extending between the lip guiding face 20 and the sash guiding face 35.

20 The arrangement of said faces is such that the portion of the integral rib formed in part by the fillet portion 33 is wider than the spring guiding face 28, the fillet portion imparting a massive form to the inner portion 25 of the rib, whereby liability of breakage of the rib from the casing member 13 is reduced and the fillet portion compensating for the reduction of the cross section of the rib caused by the formation of the wide outer face 21 30 thereon. This is a marked advantage it being evident that the member 13 would be rendered useless and require replacement if a considerable portion of the rib were broken off.

35 Another advantage of the described form of the rib is, that the beveled face 33 cooperates with the narrow wall of the screen groove in forming a recess 32 in which the lip 31 is exposed, to permit its displacement by a 40 finger or a suitable tool, into the screen groove, as shown by Figure 4. When the lip is thus displaced the screen may be moved outwardly, in the direction indicated by the arrow in Figure 4, and thus removed from 45 the window casing.

Each of the two upright members 24 of the screen frame may be provided with the described groove and spring, as shown by Figure 7, the inward displacement of the lip of 50 either spring permitting the removal of the screen from the casing.

The spring-guiding face 22, and the portion of the spring bearing thereon, may be transversely flat, as shown by Figure 2, or 55 curved, as shown by Figure 4. Only one of the upright members 24 of the screen frame may be provided with the described groove and spring, the other member 24 being provided with a shallow groove 35, contacting with the rib face 22, as shown by Figure 8.

The movability of the sash 17 is such that it 60 may be moved to expose the opening 32 and permit access to the lip 31, as indicated by 65 Figure 4.

I claim:

A window casing including a vertical outside member having a sash guiding face 35 arranged to bear on a complementary face on a sash, and a longitudinal screen guiding rib integral with said member and projecting from the sash-guiding portion thereof, said rib having a wide outer longitudinal face 21 in a plane parallel with the outer side of said casing member and offset inwardly therefrom, the face 21 being arranged to have an extended insect-excluding bearing on a complementary face of a screen frame, a narrow inner face 20 parallel with the outer face, offset from the sash guiding face 35 and arranged to guide a lip on a screen frame 70 spring, a spring-guiding face 22 between the inner and outer faces, and a reinforcing fillet portion 33 integral with the casing member 75 and rib and having a beveled face 33^a extending between the lip guiding face 20 and the sash guiding face 35, the arrangement of 80 said faces being such that the portion of the integral rib formed in part by the fillet portion is wider than the spring guiding face 28, the fillet portion imparting a massive form to the inner portion of the rib, whereby liability of breakage of the rib from the casing member is reduced, the fillet portion compensating for the reduction of the cross section of the rib caused by the formation of 85 the wider outer face 21 thereon.

In testimony whereof I have affixed my signature.

AINSLEY J. VINCENT.
